CONTROL DEVICE FOR CONTROLLABLE APPARATUS

Richard C. Marholz and Alexander W. Plensler,
Chicago, Ill., assignors to Belmont Radio Corporation, Chicago, Ill., a corporation of Illinois

Application December 12, 1938, Serial No. 245,078

12 Claims. (CL. 74—10)

Our invention relates in general to control apparatus, and more in particular to a manually operated automatic tuning device for radio receivers.

A number of manually operated automatic tuning devices for radio receivers, including those disclosed in Plensler Patent No. 2,130,153, issued Sept. 13, 1938, and copending Plensler application Serial No. 194,634, have been found satisfactory for their particular purpose. The present application is concerned with an invention representing another solution to the problem of providing a simple, low cost, yet highly efficient apparatus for manual automatic tuning of a radio receiver, as well as for the general control of controllable apparatus.

An object of the present invention is to provide an improved manually operated push button tuner.

A further object of our invention is to provide control apparatus operated upon a straight line pushing movement of an actuator to rotate a shaft substantially through 180° without the use of link or gear mechanism.

A still further object of the invention is to provide a compact, sturdy control unit which may be operated with a relatively small force to an accurate operated position.

Other objects and advantages of our invention will be apparent from the following description, taken with the drawing, in which:

Fig. 1 is a front elevation of the tuning and indicating structure of our invention.

Fig. 2 is a fragmentary view of the complete control and indicating apparatus of our invention, with the top of the housing for the apparatus cut away, and taken substantially along the line 2—2 of Fig. 1.

Fig. 3 is a vertical sectional view along the line 3—3 of Fig. 2. This shows the control apparatus in normal idle position.

Fig. 4 is a sectional view similar to Fig. 3, with one control unit and an actuator in operated position, with similar apparatus in the background shown in idle position.

Fig. 5 is a fragmentary detail view in section of one of the control units as shown in Figs. 2, 3 and 4.

In practicing our invention, we provide a plurality of adjustably mounted control units supported on a rotary shaft connected with the tuning apparatus for a radio receiver. Each control unit comprises a pair of cam portions rigid with respect to one another and with the cam surface of one cam portion extending in a di-

rection substantially opposite to the cam surface of the other cam portion. Each cam portion is provided with a stop portion at one end of the cam surface, and the two stop portions in each control unit are positioned relatively adjacent but separated from one another. The control unit is rotated in one direction or the other, depending upon the particular cam portion engaged by means of an actuator moving in a straight line toward the control unit and having a pair of engaging portions thereon, with one engaging portion adapted to contact a corresponding cam surface to rotate the control unit until the two engaging portions are in engagement with the corresponding stop portions on the control unit. Means are provided for guiding the actuator in a straight line movement, and a return spring is connected thereto for returning the actuator from an operated to an idle position. Indicating means connected with said automatic tuning structure show the tuned position of the radio receiver, and manual means for tuning the receiver entirely over a range of signal frequencies is also connected with said indicator and acts in setting the control units to various angular positions with reference to the rotary shaft.

Referring now to the drawing, Fig. 1 illustrates the front panel 10 of a housing 11 for carrying the control apparatus, it being understood of course that the housing may also be a radio receiver cabinet. A plurality of push buttons 12 are secured to corresponding movable elements in the control apparatus, and a knob 13 is also provided for manual tuning of a condenser or other tuning unit over the entire range of frequencies being received by the radio apparatus. The position of the tuning unit is indicated by a pointer 14 movable over a scale 16 and visible through a dial opening 17 in the front panel of the housing. The radio receiver may be turned "on" or "off" and the volume controlled by a knob 18 likewise available in front of the panel.

The control apparatus includes a rotary shaft 19 journaled in a pair of frame plates 21 and is either integral with or directly connected to the shaft for the radio receiver. A plurality of control units 23 are mounted for angular adjustment with reference to the shaft 19 and are normally frictionally retained thereon against rotation with reference to such shaft. The control units are selectively rotated to in turn rotate the shaft 19 by means of corresponding actuator units 26 having body portions mounted and

guided for straight line movement in the front and back frame plates 27 and 28 respectively.

A push button 12 is secured at the front end of each of the actuators and projects through the housing 11 for finger engagement. The actuators 26 are each normally retained in an idle position by means of a spring 29, and each corresponding control unit remains in the angular tuned position to which it is rotated upon movement of an actuator, as will be hereinafter described.

Each control unit 23, as shown particularly in Figs. 3, 4, and 5, comprises a pair of substantially identical cams 31 which are preferably stamped out with a cam portion extending over substantially 180° thereof, and each having a cam surface 32 thereon with a shoulder or stop portion 33 at one end of the cam surface. The body of each cam at the center thereof is embossed to provide a cup-shaped portion 34, and the two cams are rigidly secured together into a control unit with the embossed portions fitting back to back as shown in Fig. 5 to adequately space the cams apart axially for cooperation with the actuator as will be explained. The cam surfaces overlap so that there will be no "dead center" so far as actuation is concerned, and to correspond with the spaced apart engaging rollers. The embossed portions, and hence the two cams in each control unit, are suitably rigidly secured together as by stamping out a pair of portions indicated by the reference character 36 and peening one over the other in a manner such that the securing portions extend into the cavity 34 on one side of the control unit (Fig. 5). The projection at 36 resulting from such fastening also acts to limit the angular movement of the control unit with reference to the shaft 19 to approximately 180°, as will be hereinafter explained.

A channel 38 is provided intermediate the two cams in each control unit at the wall of the embossed portion to permit the legs 39 integral with the actuator 26 and extending at right angles to a body portion 41 to pass therethrough to be slidably supported and guided at the rear frame plate 28. The body portion has an offset shank 42 extending through the front frame plate 27 of the tuning unit for receiving a button 12 thereon. A pair of rollers 43 are each rotatably mounted at the body portion 41 for the actuator and are positioned on opposite sides thereof for engagement with corresponding axially separated cam surfaces 32 when the actuator is pressed inwardly in a straight line movement. Each roller is thus off-center with respect to a line between the vertical midpoint of the body 41, and the rotary shaft 19 so that considerable leverage is applied to the engaged cam surface. The particular cam surface 32 engaged in a control unit by a roller 43 depends upon the angular position of the control unit when the actuator is pressed inwardly. With a control unit in the position shown in Fig. 3, the roller 43 on the outside of the actuator as viewed in Fig. 3 engages the corresponding cam surface 32 shown entirely in full line, and rotates the control unit until each roller 43 is in engagement with a corresponding stop portion or shoulder 33, as shown in Fig. 4. This stopped position corresponds with the angular position of the control shaft 19 in a predetermined tuning position for the condenser 22. Each actuator 26 is guided and maintained in a horizontal position, so far as the line of movement is concerned, and vertical so far as the width is concerned, by openings 44 in the frame 75

plate 28 corresponding in cross section to the cross sectional dimensions of the legs 39, and a similar opening 46 in the front frame plate 27. This is shown clearly in Figs. 3 and 4.

Each control unit 23 is supported on the shaft 19 by a pair of identical friction washers 47 fitting within the cavities 34 in the cams, and each washer has a key portion 48 fitting in a corresponding keyway 49 in the shaft 19 so as to prevent angular movement of the washer relative to the shaft. Each washer has a pair of shoulders 51 spaced apart approximately 180° for engagement by the projection 36 in the control unit to limit the rotary adjustable movement of each control unit to approximately 180° or an amount corresponding to the total rotary movement of the condenser 22 or any other similar tuning unit for the radio receiver. The washers 47 are movable axially on the shaft 19 in combination with spacing collars 52 on the shaft intermediate each control unit and a washer 53, as well as a spring washer 54, all of which cooperate in applying or varying the frictional pressure on the control units. This entire assembly, including the axially movable elements described, moves to the right to apply frictional pressure on the control units as a wing nut 56 is tightened onto the threaded portion 57 of the shaft 19, or opens up to permit angular adjustment of each control unit as the wing nut is unscrewed on the shaft. A stop arm 58 secured to the shaft at the right-hand end of the movable assembly, as viewed in Fig. 2, acts to limit the axial movement of such assembly in that direction.

The condenser 22 is rotated over the entire range of frequencies at which it can be tuned by means including the tuning knob 13, a crown gear 61 secured to the shaft 19, and a pinion gear 62 meshing with said crown gear. The pinion gear 62 is rotated by means of a pair of bevelled friction discs 63 and 64, with the first disc rotating with the pinion gear 62, and the latter disc 64 secured to a shaft 66 carrying the knob 13. A spring 67 normally presses the shaft 66 outwardly to disengage the friction discs 63 and 64. Engagement between the two discs is of course provided by pressing in on the knob 13, after which the shaft 19 may be rotated in one direction or the other through the elements just described. The angular position of the shaft 19 is indicated by the pointer 14 moving over the dial scale 18 and carried on a shaft 68, which in turn is secured to a gear 69 meshing with the pinion gear 62.

The angular position of the control units 23 on the shaft 19 is also indicated by the pointer 14, inasmuch as the connection to said pointer through the gear 69, the pinion gear 62 and the crown gear 61, is always maintained irrespective of the mechanism initiating movement of the shaft 19.

Assuming that the control units are in set position and it is desired to change the angular relation of one or more of the control units with reference to the shaft 19, such shaft is rotated either by the wing nut 56 or the knob 13 to a position such that the stop arm 58 engages a corresponding stop lug 59 on the frame plate 21. The rotation is in such direction that continued movement of the wing nut 56 in the same direction after the shaft 19 is stopped, will unloosen the wing nut and remove the frictional pressure on the control units. By engaging the friction discs 63 and 64 as above explained, the shaft 19 may then be turned until the condenser 22 is in

a desired tuning position. Holding the friction discs 63 and 64 engaged to maintain the shaft 19 against movement, a selected button 12 is pushed inwardly to engage its corresponding control unit, and the control unit is rotated with reference to the held shaft 19 until the rollers 43 engage the stop shoulders on the cams 31, as shown in Fig. 4. This operation may be repeated with reference to each control unit or it may be followed with only a single control unit. After the desired settings have been accomplished, the wing nut is rotated in a direction to thread the same onto the shaft 19 until the stop arm 58 engages the opposite lug 59 and then continued rotation of the wing nut will move the control unit assembly to the right against the stop arm 58 to apply sufficient frictional pressure on the control units to hold the same. After this, the buttons 12 may be pushed selectively to rotate a corresponding control unit 23 as previously described and move the shaft 19 to a predetermined angular position. After the selected actuator 26 has been pushed to the tuned position, the spring 29 returns the same to idle position, with the back of the body portion 41 of the actuator engaging stop cushions 72 on the front plate 27 of the tuner unit.

In our invention, therefore, we provide a simple, compact control device for a radio receiver or other controllable apparatus which is operated by a straight line movement, and this straight line movement is transposed into rotary movement substantially 180° in angular distance without intermediate links or gearing as is commonly employed. With the actuators 26 provided in such a configuration that identical members are employed throughout the device, and yet may be reversed in position, alternate actuators are staggered with one shank 42 extending through a bottom opening 46 in the frame plate 21, and the next adjacent shank extending through a top opening 46 in such front plate. This makes it possible to use wide push buttons 12 as shown in Fig. 1, providing ample surface for pressing engagement, and yet occupying a relatively small space at the front panel of the housing 11 and within the housing itself.

Although we have illustrated and described our invention in its preferred embodiment, it is understood that our invention is not limited thereby, but is limited only by the scope of the appended claims.

We claim:

1. A control device for controllable apparatus, including frame means, a rotary shaft mounted in said frame means, an actuator supported in said frame means for linear movement toward said rotary shaft, and means on the rotary shaft engageable by said actuator for transposing linear movement of the actuator into rotary movement of the shaft, said means comprising a pair of cams, with the cam surfaces thereof spaced apart axially, but with said cams operatively connected and rigid with respect to one another and normally retained on said shaft against movement relative thereto.

2. A control device for controllable apparatus including a rotary control unit for angular adjustment to various predetermined control positions, said unit comprising a pair of cams operatively connected and rigid with respect to one another, with the cam surfaces thereof extending in opposite directions with reference to one another, and each cam having a shoulder portion at one end of the cam surface, and an actu-

ator supported on said device having a pair of spaced apart projections and movable toward said control unit with one projection engaging one of the cam surfaces to move said unit therewith until each projection is in engagement with a corresponding cam shoulder.

3. A control device for controllable apparatus, including frame means, a control unit rotatably mounted in said frame means comprising a pair of cams operatively connected and rigid with respect to one another, but with the cam surfaces of said cams spaced apart axially from one another, with each of said cam surfaces having a stop portion thereon, and means for rotating said control unit, said rotating means including an actuator supported in said frame means for linear movement having a pair of engaging portions thereon, with one of said engaging portions acting to engage one of the cam surfaces to rotate the control unit to a position at which each engaging portion on said actuator is in engagement with a corresponding stop portion on a cam surface.

4. A control device for controllable apparatus, including frame means, a control unit rotatably mounted in said frame means having thereon a pair of cam surfaces extending substantially in opposite directions with respect to one another and spaced apart axially of the control unit, means for rotating said control unit including a linearly movable actuator supported in said frame means for movement toward and away from said control unit, said actuator having a pair of engaging portions with each portion adapted for engagement with one cam surface or the other, and means on said control unit for arresting the movement of the actuator in a linear direction toward said control unit and simultaneously therewith arresting rotary movement of said control unit at a predetermined control position.

5. A control device for controllable apparatus, including frame means, a rotary shaft mounted in said frame means, a control unit supported on said shaft and normally frictionally retained on said shaft against movement relative thereto, said control unit comprising a pair of substantially identical cams with each of said cams including an apertured embossed body portion and a cam surface at one edge thereof, with said cams being rigidly secured together at the embossed portions with such embossed portions in a back to back position, and with said secured cams mounted on the rotary shaft at the apertures in the embossed portions, and an actuator supported in said frame means for movement in a direction toward said rotary shaft for engaging one cam surface or the other and rotating said control unit to a position at which both cam surfaces are engaged by said actuator.

6. A control device for controllable apparatus including a rotatably mounted shaft, a control unit supported on said shaft and normally frictionally retained on said shaft against movement relative thereto, said control unit comprising a pair of substantially identical control members with each of said members having an apertured embossed body portion and an engaging surface at one edge thereof, with said members positioned with the embossed portions in back to back relation and being rigidly secured together in such position, a projecting portion on one of the embossed portions of said members, and with said secured members mounted on the rotary shaft at the apertures in the embossed portions,

a friction washer on each side of said control unit keyed on said shaft against rotational movement relative thereto but axially movable thereon, with at least one of said washers having a pair of spaced-apart stop shoulders thereon for engagement with said projecting portion at said embossed portion for limiting the angular movement of the control unit with reference to the shaft, means for varying the frictional pressure intermediate said washers and said control unit, and actuating means supported in said frame means for contacting one of the two engaging surfaces upon movement of said actuating means to rotate said control unit to a position at which both engagement surfaces are contacted by said actuating means.

7. A control device for controllable apparatus including frame means having a pair of oppositely disposed frame plates, a control unit rotatably mounted in said frame means having a pair of engaging edges and stop means with said engaging edges spaced apart axially of the control unit, and means for rotating said control unit comprising a linearly movable actuator supported in said frame means and having thereon an actuator shank, a body portion, and a guide leg, with the guide leg parallel with the actuator shank and on a side of said body portion opposite thereto, said actuator shank being slidably supported in a corresponding aperture in one of the frame plates and said guide leg slidably supported in the other frame plate, and said body portion having a pair of engaging portions thereon, with one engaging portion adapted for engagement with a corresponding engaging edge on said control unit to rotate said control unit to a position at which each engaging portion is in engagement with said stop means on said control unit.

8. A control device for controllable apparatus including frame means having a pair of oppositely disposed frame portions, a control unit rotatably mounted in said frame means, including a pair of engaging edges axially spaced apart and rigid with respect to one another, means for rotating said control unit including a linearly movable actuator supported in said frame means including a body portion having a pair of engaging portions and a pair of oppositely disposed guide extensions integral with said body portion and at right angles thereto, with one of said extensions having a push button thereon, and the other of said extensions slidably supported in one of said frame portions and positioned intermediate the two engaging edges, with one of said engaging portions contacting an engaging edge of said control unit upon linear movement of said actuator to rotate said control unit to an angular position at which each engaging portion is in contact with a corresponding engaging edge.

9. A control device for a radio receiver including frame means, a rotary shaft mounted in said frame means, control means mounted on said shaft for controlling the angular rotation of said shaft, said control means including a pair of

cam-shaped edges spaced apart in an axial direction but rigid with respect to one another with each of said edges extending angularly a distance no more than 180°, and extending in an opposite

5 angular direction with respect to one another, but positioned in a manner so as to overlap at a corresponding adjacent end of each edge, and means for engaging one edge or the other to rotate said control means to a position at which both cam edges are engaged.

10. A control device for a radio receiver including frame means, a rotary shaft mounted in said frame means, control means mounted on said shaft for controlling the angular rotation of said shaft, said control means having a pair of engaging edges spaced apart in an axial direction but rigid with respect to one another, and means for contacting one engaging edge or the other to rotate said control means to a position at which both 15 engaging edges are contacted, said contact means including an actuator slidably mounted in said frame means and having a body portion positioned in the frame at right angles to the rotary shaft and intermediate said spaced apart edges, and a contact projection at each end of said body portion on opposite sides thereof with one projection adapted to contact the one engaging edge and the other projection adapted to contact the other engaging edge.

30 11. Control mechanism for controllable apparatus including rotary control means, and substantially linearly movable control means, frame means supporting said latter means for substantially linear movement, with one of said control 35 means having a pair of cam surfaces thereon laterally disposed and at a portion of each overlapingly disposed but being fixed with respect to one another, with said rotary control means being moved directly by the linearly movable control means to transpose linear movement of the latter means into rotary movement in the rotary control means, and with movement of both said control means continuing to a predetermined control position.

45 12. Control mechanism for controllable apparatus including a plurality of linearly movable actuator means, frame means supporting said actuator means for linear movement, and a plurality of rotary control means corresponding to said actuator means, with each control means being selectively rotated directly by its corresponding actuator means to transpose the linear movement of said actuator means into rotary movement in said control means, each of said rotary control means having a pair of radially extending portions with engaging surfaces thereon axially displaced but fixed with respect to one another, with a corresponding actuator means being linearly movable to engage one engaging 55 surface or the other to directly rotate said control means to a position at which said actuator means is in engagement with both extending portions on said control means.
